UNITED STATES PATENT OFFICE.

WILLIAM C. HILLS, OF COLBURN, I. O.

PENCIL.

No. 919,167.

Specification of Letters Patent. Patented April 20, 1909.

Application filed June 29, 1908. Serial No. 440,951.

To all whom it may concern:

Be it known that I, WILLIAM C. HILLS, a citizen of the United States, residing at Colburn, in the county of Bonner, State of Idaho, have invented certain new and useful Improvements in Pencils; and I do hereby declare the following to be a full, clear, and exact description of the invention, such as will enable others skilled in the art to which it appertains to make and use the same.

The invention relates to a pencil and more particularly to the class of pencils having a detachable ferrule carrying an eraser at one end and a knife at the other end.

The primary object of the invention is the provision of a pencil having at one end an emery strip circumscribing the same, a removable ferrule adapted to inclose the emery strip, a knife mounted upon said ferrule at one end thereof and an eraser secured in the opposite end of said ferrule.

Another object of the invention is the provision of a pencil having a removable ferrule carrying a knife and an eraser, the said ferrule adapted to fit over one end of the pencil when the knife is not to be used and said pencil carrying an emery strip to form a sharpener for the knife, the said emery strip being protected by the ferrule when in position on the pencil.

With these and other objects in view the invention consists in the construction, combination and arrangement of parts as will be hereinafter more fully described and as illustrated in the accompanying drawings which disclose the preferred form of embodiment of the invention.

It is to be understood that changes, variations and modifications will be made such as come properly within the scope of the claims hereunto appended without departing from the spirit of the invention.

In the drawings:—Figure 1 is a side view of a pencil with the removable ferrule in position thereon. Fig. 2 is a similar view partly in section. Fig. 3 is a fragmentary view showing the end of the pencil for receiving the ferrule and the same being broken away. Fig. 4 is a section on the line 4—4 of Fig. 2. Fig. 5 is a detail perspective view of the removable ferrule carrying the knife and eraser.

Similar reference characters indicate cor-

responding parts throughout the several views in the drawings.

In the drawings, the numeral 6 designates a wooden pencil of the ordinary construction having at its upper end an annular recess 7 to receive a circular emery strip 8 which latter lies flush when secured in said recess 60 with the outer face of the pencil. At the end of the pencil 6 carrying the emery strip 8 there is provided in the outer face of the pencil an elongated slot or recess 9 to form a pocket for the reception of a knife blade 10 riveted as at 11 to the inner face of a removable ferrule 12 forming a sleeve detachably fitting onto the end carrying the emery strip 8 of the pencil. Immediately below the said emery strip 8 and circumscribing the pencil 6 is a fixed ferrule 13 which latter overlies a greater portion of the recess or slot 9 and is adapted to protect the knife blade 10 when inserted in the said slot or recess 9 and to hide the said knife blade 75 from view after the removable ferrule 12 has been connected to the pencil end.

Mounted in the removable ferrule 12 at the end opposite that carrying the knife blade is an eraser 14 preferably formed of 80 rubber and which is held securely within the said ferrule by inwardly bent biting spurs 15 disposed at diametrically opposite points at the upper edge of the removable ferrule.

To connect the removable ferrule 12 to the pencil 6 the knife blade 10 is inserted in the recess or slot 9 and by pushing upon the said ferrule 12 the same is brought into position to cover the emery strip 8 fixed to the end of the pencil. This removable ferrule 12 90 when mounted upon the pencil abuts against the upper edge of the fixed ferrule 13 circumscribing the pencil immediately below the emery strip at the end thereof.

What is claimed is—

1. The combination with a pencil having a slot in its face at one end thereof, of a strip of emery circumscribing the slotted end of the pencil, a removable ferrule adapted to fit upon the slotted end of the pencil and inclose the emery strip, and a knife blade carried at one end of the ferrule and adapted to fit within the slot in the pencil.
2. The combination with a pencil having a slotted end, of an emery strip mounted upon the slotted end of the pencil, a ferrule

fixed to the pencil immediately beyond the
emery strip and overlying a portion of the
slot, a removable eraser supporting ferrule
adapted to fit over the emery strip, and a
5 knife blade carried at one end of the remov-
able ferrule and adapted to engage the slot
and be protected by the fixed ferrule.

In testimony whereof, I affix my signa-
ture, in presence of two witnesses.

WILLIAM C. HILLS.
